US00D839056S

(12) **United States Design Patent** (10) **Patent No.:** **US D839,056 S**
(45) **Date of Patent:** **** Jan. 29, 2019**

(54) **CONTAINER**

(71) Applicant: **YETI Coolers, LLC**, Austin, TX (US)

(72) Inventors: **Mark Carlson Rane**, Austin, TX (US);
Edward Abante, Austin, TX (US);
Andrew Winterhalter, Austin, TX (US);
Desiree Hunter, Austin, TX (US);
Robert Throop, Austin, TX (US)

(73) Assignee: **YETI Coolers, LLC**, Austin, TX (US)

(**) Term: **15 Years**

(21) Appl. No.: **29/614,325**

(22) Filed: **Aug. 17, 2017**

(51) **LOC (11) Cl.** **07-01**

(52) **U.S. Cl.**

USPC **D7/608**

(58) **Field of Classification Search**

USPC D7/603–608, 612–615, 629, 630,
D7/509–511; D9/500, 503, 504, 516,

Primary Examiner — Terry A Wallace

(74) *Attorney, Agent, or Firm* — Banner & Witcoff, Ltd.

(57) **CLAIM**

The ornamental design for a container, as shown and described.

DESCRIPTION

FIG. 1 is a top, front, left perspective view of a container showing our new design;

FIG. 2 is a bottom, left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The uneven-length broken lines represent unclaimed boundaries of the claimed design. The even-length broken lines showing the remainder of the container represent unclaimed subject matter and form no part of the claimed design.

1 Claim, 7 Drawing Sheets
